(57) **CLAIM**

The ornamental design for an utility terrain vehicle, as shown and described.

DESCRIPTION

FIG. 1 is a front elevational view of an utility terrain vehicle showing my new design at an enlarged scale;
FIG. 2 is a rear elevational view thereof at an enlarged scale;
FIG. 3 is a left side view thereof;
FIG. 4 is a right side view thereof;
FIG. 5 is a top plan view thereof;
FIG. 6 is a perspective view thereof; and,
FIG. 7 is another perspective view thereof.
The broken lines shown form no part of the claimed design.
